UNITED STATES PATENT OFFICE.

FRANK LA OTIS LATHROP, OF WALLINGFORD, CONNECTICUT, ASSIGNOR TO H. L. JUDD COMPANY, OF WALLINGFORD, CONNECTICUT, A CORPORATION OF NEW YORK.

CURTAIN ROD AND BRACKET.

1,070,144.

Specification of Letters Patent. Patented Aug. 12, 1913.

Application filed May 20, 1913. Serial No. 768,733.

To all whom it may concern:

Be it known that I, FRANK LA OTIS LATHROP, a citizen of the United States, residing at Wallingford, New Haven county, 5 State of Connecticut, have invented certain new and useful Improvements in Curtain Rods and Brackets, of which the following is a full, clear, and exact description.

This invention relates to an improved 10 form of curtain rod and supporting bracket structure, wherein a form of support is provided for the rod end, which support provides a substantial bearing for the rod end and means for quickly and detachably 15 securing the rod end thereto.

The invention further resides in certain specific details of construction hereinafter pointed out.

A preferable embodiment of the invention 20 is described in detail in the following specification taken in connection with the accompanying drawings forming a part thereof.

In these drawings:—Figure 1 is a plan view of a rod and bracket structure embodying the present invention. Fig. 2 is a 25 sectional view taken longitudinally of the supporting bracket and on an enlarged scale. Fig. 3 is an end view of the bracket. Fig. 4 is a view in side elevation of the 30 parts shown in Fig. 2. Fig. 5 is a fragmentary view, partly in section, of the curtain rod end coöoperating with the bracket.

Referring to the drawings by numerals, 1 35 and 2 designate the coöperating sections of a tubular telescoping curtain rod of the “goose-neck” type, the terminal ends of the rod structure being provided with enlargements 3 having an annular groove 4 formed therein and having a recess 6 formed in 40 their end faces. The annular groove 4 provides annular abutment flanges 5 which are adapted to engage certain retaining or stop members carried by the bracket as will be 45 hereinafter described. As the construction 50 of a single rod end and bracket is alone involved, I will describe only one such end structure, as both shown in the drawings are identical.

The supporting bracket which coöperates 55 with the rod end is preferably formed of an integral piece of sheet metal stamped to provide a base plate 7 arranged to be secured to a suitable support and having an offset portion 8 extending at right angles and outwardly therefrom, this offset portion being angular in cross section and provid-

ing a cupped offset having an arc greater than a semi-circle and of slightly greater diameter than the end 3 of the curtain rod. 60 Adjacent the base plate 7 the side walls of the offset portion are extended as at 9 to provide guide flanges for the end 3 of the curtain rod, by means of which said rod end may be guided to the base of the offset 8. Adjacent the base plate 7 and in circumferential alinement are a plurality of 65 stop lugs 10, which are preferably struck up from the material of the offset portion and which extend in an arc greater than a semi-circle and for substantially the full 70 extent of the cupped offset. In the drawings, I have shown three such lugs 10, which will provide a three point grip for the end of the rod as will be seen later, these points of engagement being above and below the 75 center of the rod. Struck from the base plate 7, and projecting outwardly therefrom toward the line of lugs 10 is a spring keeper tongue 11, having thereon a protuberance 12 arranged to engage in the recess 6 of 80 the rod end. The distance between this keeper tongue and line of the inner face of the lugs 10, is less than the distance between the annular groove 4 of the rod end and its end face. These brackets may be arranged with the length of their base plate 85 7 extending either vertically or horizontally of a suitable support such as the window frame, as shown in Fig. 1. Whatever the arrangement, it will be evident that the 90 rod end 3 may be moved longitudinally of the bracket, guiding between the flanges 9 and bringing its annular groove 4 over the stop lugs 10. The depth of this groove is 95 preferably such as to bring the periphery of the rod at its extremity to rest upon the base of the offset 8, but this is not necessarily the case and the rod end may be supported entirely by the lugs 10. As the rod end is moved longitudinally of the base plate 100 7, it will engage the stop lug 10 as aforesaid, positioning its annular abutment walls 5 on either side of the stop lugs and bringing the recess 6 in its end face in line with 105 the protuberance 12 of the spring keeper, which will snap into engagement with said recessed end and detachably hold the rod end seated within the cupped offset with its annular abutment flange 5 held against the stop lugs 10. As these stop lugs extend both 110 above and below the center line of the rod, it will be seen that a firm support is af-

forded, which prevents the rod end from tipping in the bracket and from becoming disengaged therefrom. Nevertheless, in order to disengage the rod end from the bracket, it is only necessary to move the rod end with slight force in the direction of the length of the base plate 7, whereupon the spring keeper 11 will be disengaged from the rod end and the same may be moved 10 away from the cupped offset and out of engagement with the lugs 10 thereof.

It will be noted here, that the division of the annular groove 4 in the end of the rod provides two abutment flanges, one of which 15 receives and transmits to the lugs 10 and bracket, end pull on the rod and the other of which transmits to said lugs, end thrust. Because of the support afforded above and below the center line of the rod, the rod ends 20 are fully able to take care of such strains and are furthermore prevented from moving from strain-receiving engagement with the lugs of the cupped offset by reason of the interlocking engagement of the spring 25 tongue 11. The form of bracket described not only provides a most useful support for the end of a rod constructed as described, but is, itself, in its specific form, a very desirable article commercially, inasmuch as it 30 may be readily stamped from a single piece of sheet metal, as will be obvious from the showing in the drawings.

It will be obvious, while I have shown both ends of the rod end similarly formed 35 and coöperating with the same form of bracket, that the invention proper relates to the construction of a coöperating rod end and bracket support *per se*.

While I have described a preferable embodiment of my invention, it will be obvious that the same is susceptible of change 40 in structure and in the relative arrangement of parts within the spirit of the invention and the scope of the appended claims.

45 What I claim, therefore, and desire to secure by Letters Patent is:—

1. In a device of the character described, a base arranged to be secured to a support and having an outwardly offset portion provided with a plurality of spaced stop members, a curtain rod arranged to be supported at one end by said offset portion and having end abutment means arranged to engage said stop members, and means arranged to engage 50 said rod and hold its abutment in engagement with said stop members.

2. In a device of the character described, a base arranged to be secured to a support and having an outwardly offset portion 60 cupped in cross section and provided with a plurality of spaced and alined stop members projecting therefrom, a curtain rod arranged to be supported at one end by said

offset cupped portion and provided at such end with an annular abutment flange arranged to engage said stop members, and a spring member carried by said base and arranged to engage said rod end to hold its abutment flange in engagement with said stop members. 65

3. In a device of the character described, a base arranged to be secured to a support and having an outwardly offset portion cupped in cross section and provided with a plurality of spaced and alined stop members projecting therefrom, a curtain rod arranged to be supported at one end by said offset cupped portion and provided at such end with an annular abutment flange arranged to engage said stop members, and a 70 spring member carried by said base and arranged to engage said rod end to hold its abutment flange in engagement with said stop members, said stop members engaging said flange at points below and above the 75 center of said rod.

4. In a device of the character described, a base arranged to be secured to a support and having an outwardly offset portion, cupped in cross section and provided at 80 alined points adjacent said base with a plurality of spaced stop lugs, a curtain rod arranged to be supported at one end by said offset cupped portion and having at such end an annular abutment flange arranged to 85 engage said alined lugs, and a spring keeper carried by said base and arranged to engage the end face of said rod to hold said abutment flange in engagement with said stop lugs. 90

5. In a device of the character described, an integral sheet metal supporting bracket comprising a base plate, an annular cupped portion offset and extending outwardly therefrom, said cupped portion having an 105 arc greater than a semi-circle, a plurality of lugs projecting from said cupped offset at circumferentially alined points adjacent said base plate, said lugs extending in an arc greater than a semi-circle, a spring tongue 110 carried by and extending from said base plate toward said lugs; and a coöperating curtain rod having its end arranged to seat within and be supported by said cupped portion, said rod end being provided with 115 an annular groove therein arranged to receive said stop lugs at points below and above the center of said rod, and the end face of said rod being engaged by said spring tongue to hold a wall of said groove 120 in engagement with said lugs.
